UNITED STATES PATENT OFFICE.

JAMES E. ALLEN AND HENRY G. SCHWOEPPE, OF LOGANSPORT, INDIANA, ASSIGNEES
TO BOYER FIRE APPARATUS COMPANY, OF LOGANSPORT, INDIANA, A CORPORATION
OF INDIANA.

LADDER CLAMP.

Application filed January 9, 1928. Serial No. 245,423.

This invention relates to means for clamping a number of ladders to a fire wagon or truck, and has for its primary objects the supplying of such means adjustable to a wide range of ladder structures; simplicity of construction; positive retaining of the ladders; and quickness of operation. Other objects will become apparent in the following description of one form of the invention as shown in the accompanying drawings, in which—

Fig. 1, is a side elevation of a clamp, on a reduced scale, embodying the invention, shown in reference to ladders on the side of a hose wagon bed;

Fig. 2, a transverse section on the line 2—2 in Fig. 1, showing a top plan view of the clamp;

Fig. 3, a vertical section on the line 3—3 in Fig. 2;

Fig. 4, a side elevation of the cam block; Fig. 5, a forward end elevation of the clamp; and

Fig. 6, a rear end elevation of the clamp.

Like characters of reference indicate like parts throughout the several views of the drawings.

To the side 10 of the bed of a hose wagon is secured a vertically disposed ladder iron 11 which has a foot 12 extending horizontally therefrom on which the ladders 13 and 14 are placed to rest on their side rails. A similar iron and foot (not shown) supports the other ends of the ladders.

On the ladder iron 11 is mounted the clamp body 15, a slot being formed on the inner side of the body to engage snugly over the iron, and the ears 16 and 17 project up and down, respectively from the body 15 along the iron 11 to have bolts 18 passed therethrough into the iron 11 to secure the body 15.

The forward side of the body 15 has two spaced apart ears 16 and 17 extending rearwardly and outwardly, between which is pivotally secured the positioning block 21 by the pin 22. On the forward side of the body 15 is a box-like outwardly and rearwardly extending housing 23, and between this housing 23 and the ears 16 and 17, the body 15 is formed to receive therein a rung 24 of the inner ladder. The block 21 is curved on its rear face to engage around the rung 24 and

aid in positioning and retaining the rung 24, as shown in Fig. 2.

Eye-bolts 25 and 26 are screw-threadedly engaged in the block 21 in a spaced apart relation, as indicated in Fig. 5, and a saddle-block 27 is pivotally secured between the bolts 25 and 26 by a bolt 28 slidingly passed through the eye of the bolt 25 and one end of the block 27, and screw-threadedly passed through the eye of the bolt 26. The eye-bolts 25 and 26 are here shown of the proper length extended from the block 21 to permit the saddle-block 27 to be properly passed around the outer side of the rung 29 of the outer ladder.

The saddle-block 27 is compressively engaged against the rung 29 by the pull of the yoke 30 which is pivotally attached by its legs to the rear end of the saddle-block 27 by the pin 31, to be pulled inwardly by the cam block 32 which engages over the transverse bar of the yoke by the hook 33.

The cam block 32 is rectangular in cross section and is slidingly guided in a transverse, horizontal position to travel within the housing 23, the housing 23 being open at both its inner and outer ends. On its rear side, the cam block 32 has a slot 34 cut vertically thereacross to leave the inner shoulder 35 and outer shoulder 36, Fig. 6. Extending longitudinally through the rearwardly extending housing boss 37 is the cam shaft 38 which carries the cam 39 on its forward end within the slot 34 between the shoulders 35 and 36. An operating handle 40 is fixed to the rear end of the shaft 38 to hang normally downwardly. The cam 39 is substantially circular in contour and is mounted eccentrically of the shaft 38 to have its major portion turned inwardly when the handle 40 hangs downwardly so that the cam block 32 is thereby carried inwardly to its inmost position, as shown in Figs. 2, 3, and 6, when the greatest pressure is exerted by the saddle-block 27 on the ladder rung 29.

The face of the cam 39 is flattened on its extreme inner side, Figs. 3 and 6, so that to turn the cam 39 from the clamped position, a slightly greater pressure is exerted on the ladder rung 29 as the cam 39 is rocked over the corner "a", there being sufficient spring or elasticity in the rung 29 to permit the application of such increased pressure.

By reason of this formation of the cam face, the cam-block 27 is retained in the clamped position against accidental displacement that would release the ladders.

- 5 Since the saddle-block 27 compressively engages against the outer rung 29, the rails 42 and 43 of the ladder having the rung 29 are yieldingly pressed against the two rails 45 of the inner ladder having the rung 24 10 to carry the rails 45 against the ladder irons 11, whereby the two ladders are effectively held against any displacement until the clamp handle 40 is turned around to a vertical position.
- 15 As the handle 40 is swung outwardly around, upwardly and inwardly toward the bed side 10, the cam 39 carries the block 32 outwardly to permit the yoke 30 to be disengaged from the block hook 33 to allow the 20 saddle-block 27 to be swung outwardly and the positioning block 21 forwardly from the rungs 29 and 24 so that the ladders may be removed.

A spring 46 compressively engages between 25 the body side 10 and the cam block 32 to tend to force the cam block 32 outwardly, thereby serving not only as an aid to maintain the shoulder 35 in contact with the flat section of the cam face when the block 32 30 is in its inner clamped position but also to kick the block 32 outwardly when the handle 40 is pulled around to the upper position, and further as means to retain the handle 40 in the upper position to keep the 35 block 32 outermost until the ladders are returned to be clamped.

The forward side of the housing 23 is bored through (Fig. 2) to permit the shaft 38 and its cam 39 formed integrally thereon, to be 40 inserted from the forward side, the block 32 being similarly bored through, to permit the shaft 38 to be inserted and slid through the boss 37 to bring the cam 39 into the slot 34 on the rear side of the block 32, and 45 the handle 40 is attached to the shaft 38 from the rear end.

While we have here described the invention in the form now best known to us, it is obvious that the structure may be varied 50 considerably from the form as shown without departing from the spirit of the invention, such as for one example, the eye bolts and yoke may be lengthened so that three or more ladders may be clamped together, and we, 55 therefore, do not desire to be limited to the precise form as shown, nor any more than may be required by the following claims.

What we claim, is:

1. In a device for securing a ladder to a 60 body, a clamp body, a positioning block pivoted to the clamp body, a saddle-block, means for adjustably positioning said saddle-block from the positioning block, a cam-block slidably carried by the clamp body, means for 65 releasably engaging the saddle-block with the

cam-block, and means actuating said cam-block to pull said saddle-block toward said clamp body.

2. In a device for securing a ladder to a 70 body, a clamp body, a positioning block pivoted to the clamp body, a saddle-block, means for adjustably positioning said saddle-block from the positioning block, a cam-block slidably carried by the clamp body, means for 75 releasably engaging the saddle-block with the cam-block, and means actuating said cam-block to pull said saddle-block toward said clamp body and spring means normally extending said cam-block from said clamp body.

3. In a device for securing a ladder to a 80 body, a clamp body, a positioning block pivoted to the clamp body, a saddle-block, means for adjustably positioning said saddle-block from the positioning block, a cam-block slidably carried by the clamp body, means for 85 releasably engaging the saddle-block with the cam-block, and an actuating cam associated with the cam-block.

4. In a device for securing a ladder to a 90 body, a clamp body, a positioning block pivoted to the clamp body, a saddle-block, means for adjustably positioning said saddle-block from the positioning block, a cam-block slidably carried by the clamp body, means for 95 releasably engaging the saddle-block with the cam-block, and an actuating cam associated with the cam-block said cam having a contour whereby said saddle-block is carried by said cam-block inwardly slightly before it 100 may travel outwardly.

5. In a device for clamping a plurality of ladders to a body by engaging the rungs of the ladders, a clamp body, a rung positioning block pivoted to the clamp body, an extensible member carried by the positioning block, 105 a saddle-block pivoted to the extensible member, said positioning block swinging member, said positioning block swinging around a rung of the ladder adjacent said body and said saddle-block swinging around the outside of a rung of the outermost of said ladders, a hook member extensibly carried by the clamp body, means for detachably interconnecting said saddle-block with said hook member, and means actuating said hook member to cause said saddle-block to press on the 110 rung therebeneath.

6. In a device for clamping a plurality of ladders to a body by engaging the rungs of the ladders, a clamp body, a rung positioning block pivoted to the clamp body, an extensible member carried by the positioning block, a saddle-block pivoted to the extensible member, said positioning block adapted to 120 swing around a rung of the ladder adjacent said body and said saddle-block swinging around the outside of a rung of the outermost of said ladders, a hook member extensibly carried by the clamp body, means for detachably interconnecting said saddle-block with said 125 130

- hook member, and means actuating said hook member to cause said saddle-block to press on the rung therebeneath and means retaining said saddle-block against said rung in cooperation with the resiliency of said rung.
7. In a device for securing a ladder to a body, a clamp body, a saddle block, a cam-block slidingly carried by the clamp body, means for releasably engaging the saddle block with the cam-block, and a cam carried by the clamp body adapted to extend and withdraw said cam-block upon rotation thereof.
- 10

8. In a device for securing a ladder to a body, a clamp body, a positioning block pivot- 15 ed to the clamp body, a saddle-block supported from said positioning block, a cam-block slidingly carried by the clamp body, means releasably engaging the saddle-block with the cam block, and means actuating said 20 cam-block to pull said saddle-block toward said clamp body.

In testimony whereof we affix our signatures.

JAMES E. ALLEN.
HENRY G. SCHWOEPPE.
